(57) **CLAIM**

The ornamental design for a watch box as shown and described.

DESCRIPTION

The patent or application file contains at least one drawing executed in color. Copies of this patent or patent application publication with color drawing(s) will be provided by Office upon request and payment of the necessary fee.

FIG. 1 is a front view of a watch box showing my new design;

FIG. 2 is a back view thereof;

FIG. 3 is a top view thereof;

FIG. 4 is a bottom view thereof;

FIG. 5 is a left side view thereof;

FIG. 6 is a right side view thereof;

FIG. 7 is a front perspective view thereof;

FIG. 8 is an open perspective front view thereof; and,

FIG. 9 is a closed back perspective view thereof.

1 Claim, 9 Drawing Sheets
(9 of 9 Drawing Sheet(s) Filed in Color)
